DESIGN FOR A SHIRT OR SIMILAR ARTICLE

Vincent Zito, New York, N. Y.

Application August 17, 1946, Serial No. 132,600

Term of patent 3½ years

(Cl. D3—25)

To all whom it may concern:

Be it known that I, Vincent Zito, a citizen of the United States, residing at New York city, in the county of New York and State of New York, have invented a new, original, and ornamental Design for a Shirt or Similar Article, of which the following is a specification, reference being had to the accompanying drawing, forming part thereof.

In the drawing:

Fig. 1 is a front view of a shirt, showing my new design;

Fig. 2 is a rear view thereof; and

Fig. 3 is a fragmentary view showing the side placket.

I claim:

The ornamental design for a shirt or similar article, as shown.

VINCENT ZITO.
